CLAIM

The ornamental design for a protective cover for marine instruments on a control console, as shown and described.

DESCRIPTION

FIG. 1 is a bottom, front, and left side perspective view of a protective cover for marine instruments on a control console showing my new design;

FIG. 2 is a top, rear, and left side perspective view;

FIG. 3 is a right side elevational view;

FIG. 4 is a top plan view;

FIG. 5 is a bottom plan view;

FIG. 6 is a bottom, front, and left side perspective view of another embodiment of FIGS. 1-5;

FIG. 7 is a top, rear, and left side perspective;

FIG. 8 is a right side elevational view;

FIG. 9 is a top plan view; and

FIG. 10 is a bottom plan view thereof.
